UNITED STATES PATENT OFFICE.

WALTER L. WILKS, OF WALLINGFORD, CONNECTICUT, ASSIGNOR TO GEORGE M. HALLENBECK, OF MERIDEN, CONNECTICUT.

DESIGN FOR A HANDLE FOR SPOONS, FORKS, OR SIMILAR ARTICLES.

SPECIFICATION forming part of Design No. 33,933, dated January 22, 1901.

Application filed December 24, 1900. Serial No. 40,984. Term of patent 3½ years.

To all whom it may concern:

Be it known that I, WALTER L. WILKS, of Wallingford, in the county of New Haven and State of Connecticut, have invented and produced a new Design for a Handle for Spoons, Forks, or Similar Articles; and I do hereby declare the following, when taken in connection with the accompanying drawing and the letters of reference marked thereon, to be a full, clear, and exact description of the same, and which said drawing constitutes part of this specification, and represents a face view of a handle for spoons, forks, and similar articles, illustrating my design.

This invention relates to a design for a handle for spoons, forks, and similar articles; and the design consists in the configuration and ornamentation as herein shown and described.

As herein shown, the handle gradually tapers from its inner end outward to a point

near the outer end, from whence its edges rapidly converge, forming a tip, which is ornamented by a trefoil A. Near the center of the handle is a cluster of scrolls B, and on opposite sides of the outer end are scrolls C, which extend up to and meet the trefoil A and outline a panel D, while from the cluster of scrolls B extends a series of scrolls D, which terminate in leaf-like ends E at the inner end 30 of the handle. 25

I claim—

The design for a handle for spoons, forks, and similar articles as herein described and shown in the accompanying illustration. 35

In testimony whereof I have signed this specification in the presence of two subscribing witnesses.

WALTER L. WILKS.
